UNITED STATES PATENT OFFICE.

DAVID A. SPRINKLE, OF PENNSBORO, WEST VIRGINIA.

WOOD PULLEY.

SPECIFICATION forming part of Letters Patent No. 669,668, dated March 12, 1901.

Application filed November 17, 1900. Serial No. 36,842. (No model.)

To all whom it may concern:

Be it known that I, DAVID A. SPRINKLE, a citizen of the United States, residing at Pennsboro, in the county of Ritchie and State of West Virginia, have invented certain new and useful Improvements in Wood Pulleys; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to an improvement in wood pulleys in which the rim and arms are constructed separately and afterward joined together, and is particularly applicable to pulleys constructed with bent-wood rims; 20 and the object of my improvement is to provide constructive means for joining and binding together the driving-arms and the rim of such pulleys in a more secure manner than has been done heretofore. I attain this object by the mechanism illustrated in the accompanying drawings, in which—

Figure 1 is a perspective view of a separable wood pulley embodying my improvement; Fig. 2, a sectional view on line xx of Fig. 1, 30 and Fig. 3 a section in part of the rim and arm at right angles to the pulley-axis.

Similar letters refer to similar parts throughout the several views.

The pulley-rim I prefer to build up of three 35 separate bent-wood bands a a' a^2 , which are glued together in the process of manufacture. This construction of the pulley-rim counteracts to a large extent the warping and twisting that would occur in a bent rim made of 40 one piece. The external band a is made of hard wood susceptible of taking a smooth finish, which is best adapted for belt-driving. The internal band a^2 is also made of hard wood; but the central band a' is of soft wood, 45 such as white pine, for the following reasons: first, that a better glue-joint can be made between such surfaces than if both were hard wood; second, that the soft-wood band a' being disposed between bands a and a^2 , of hard 50 wood, will act as a cushion for jars or blows that the pulley-face may be subjected to.

The hub of the pulley is formed by the arms B and the hub-blocks b, secured together by the use of glue or cement and by the dowel-pins b^2 , of wood. The arm-lugs D are secured to the arms B in the same manner as the hub-blocks. The arm-lugs D at one end of the pulley-arms B of each pulley-section project slightly from between the arms, so as to interlock with the opposite section for 55 the purpose of maintaining the alinement of the parts.

The anchor-bolts d pass through the arm-lugs D and pulley-rim a a' a^2 and are provided with cone-shaped anchor-nuts d', made 65 of soft lead, Babbitt metal, or a metal of like character for the purpose. The anchor-bolts are provided with roughened threads or with roughened circular grooves or with indentations for the purpose of securely engaging 70 the soft-metal nuts d' cast upon them. This is accomplished by inserting the bolts in place and then pouring molten metal about the ends in the cone-shaped openings made in the pulley-rim for the purpose. The molten metal 75 fills up the small cavities presented by the grain of the wood and forms a lock to prevent the nut from turning loose. These soft nuts may, if necessary, be tightened in their seats by hammering after the metal has cooled 80 and are turned off smooth with the face of the pulley when the latter is turned in a lathe.

Before applying the anchor-bolts to the pulley the rim and arms of the same are joined together by the use of glue.

The bolts b' are for the purpose of clamping the pulley on its shaft.

I am aware that it is common practice to construct pulleys of wood throughout, that such pulleys have bent rims constructed of 90 one piece or thickness or of a number of layers put together in the manner I have described or have rims built up of a number of annular rings, each ring consisting of a number of sections, that wood arms of various 95 shapes are applied to the pulley-rims, constructed integral with the rims or built separately and afterward joined to the rims. I therefore do not broadly claim the construction I have shown and described; but 100

What I do claim, and desire to secure by Letters Patent, is—

The combination, in a wood pulley, with the rim and arms thereof, of lugs secured to the arms and adapted to fit the inside of the pulley-rim and to receive bolts for binding them to the rim; anchor-bolts passing through the arm-lugs and rim of pulley and cone-shaped nuts of soft metal which have their bearing within the pulley-rim and are flush with the face thereof, said nuts being cast in place

about the ends of the bolts, substantially as so shown and described.

In testimony whereof I affix my signature in presence of two witnesses.

DAVID A. SPRINKLE.
